F. C. TABLER

AIR INLET AND MIXING DEVICE FOR INTERNAL COMBUSTION ENGINES

Filed Oct. 25, 1919

UNITED STATES PATENT OFFICE.

FRANK C. TABLER, OF ST. LOUIS, MISSOURI.

AIR INLET AND MIXING DEVICE FOR INTERNAL-COMBUSTION ENGINES.

Application filed October 25, 1919. Serial No. 333,140.

To all whom it may concern:

Be it known that I, FRANK C. TABLER, a citizen of the United States, residing at St. Louis, Missouri, have invented a certain 5 new and useful Improvement in Air Inlet and Mixing Devices for Internal-Combustion Engines, of which the following is a full, clear, and exact description, such as will enable others skilled in the art to which, 10 it appertains to make and use the same, reference being had to the accompanying drawings, forming part of this specification.

My invention relates generally to internal combustion engines and more particularly 15 to a device in the form of a valve that is connected directly to the intake manifold of the engine, and which device, when properly operated, admits air into the intake manifold, which air is mixed with the combustible vapor passing from the carburetor 20 to the ignition chambers of the engine.

The principal objects of my invention are, to provide a relatively simple and efficient air inlet and mixing device which can be 25 readily applied to the intake manifolds of practically all forms of internal combustion engines now in general use; and to provide connections whereby said device may be regulated and controlled directly from parts 30 of the spark or gas controlling mechanisms associated with the internal combustion engine.

Further objects of my invention are, to 35 provide an air inlet and mixing valve that is self-closing; to provide a construction having a combined mixing and deflecting plate that projects into the intake manifold, said mixing plate or deflector being perforated in order to effect a thorough mixing 40 of the air with the combustible vapor passing through said manifold; to provide the device with an air inlet connection, the mouth of which is located immediately adjacent to the exhaust manifold of the engine, whereby the air taken into and through 45 the device is preheated, thereby materially increasing the efficiency of the attachment; and, further, to provide a device which can be easily and cheaply produced and which 50 will be very effective in performing its intended functions.

With the foregoing and other objects in view, my invention consists in certain novel features of construction and arrangement 55 of parts, hereinafter more fully described

and claimed, and illustrated in the accompanying drawings, in which—

Figure 1 is an elevational view of the intake manifold of an internal combustion engine, and showing my improved air inlet 60 and mixing device applied thereto.

Figure 2 is an enlarged vertical section taken approximately on the line 2—2 of Figure 1.

Figure 3 is an elevational view of the 65 attachment with parts in section and showing the device in position to admit air to the intake manifold.

Figure 4 is a horizontal section taken approximately on the line 4—4 of Figure 2. 70

Figure 5 is a fragmentary perspective view of a portion of the housing of the device and showing the ports therein.

Figure 6 is a fragmentary perspective of 75 the inner movable portion of the housing and showing the ports therein.

Referring by numerals to the accompanying drawings, 10 designates the engine cylinders, 11 the exhaust manifold, 12 the intake manifold, and 13 the tubular connection from the carburetor to said intake manifold. 80

The attachment contemplated by my invention includes a housing composed of a flat side wall 14, and an annular wall 15, 85 said housing being provided with suitable ears or projections 16 which receive screws to secure the device to the intake manifold. Formed through the annular wall 15 are ports 17 and 18 and secured in any suitable 90 manner to said annular wall is a ring 19, the opening in which communicates with the port 18. This ring projects through a suitable opening 20 formed through the wall of the intake manifold 12, and formed integral with or fixed to said ring is a plate 21 that projects into the passageway 95 through the manifold 12. This plate 21 is preferably curved in cross section and it is perforated as designated by 22 in order to 100 divide the air delivered to the intake manifold by the device into relatively small jets, thereby effecting a thorough mixture of said air with the combustible vapor passing through the manifold. 105

Secured to the annular wall 15 and surrounding port 17 is the lower end of a tubular member 23, the upper end of which terminates adjacent to the exhaust manifold 11 and the mouth or inlet end of this 110

tubular member is provided with a reticulated or foraminous strainer 24.

Arranged for rotation within the housing comprising the walls 14 and 15 is a member comprising a flat side wall 25 and an annular wall 26, the latter fitting snugly against the inner surface of annular wall 15. Secured to wall 25 is a radially projecting arm 27 which is adapted to transverse a slot 28, which latter is formed in the edge of annular wall 15 and the ends of said slot forming stops to limit the movement of said arm.

Removably positioned in the center of wall 14 is one end of a non-circular bolt 29, the opposite end of which is reduced and formed into a cylindrical member 30, which has bearing in the center of plate 25. Seated in this end of the bolt is a screw 31, the head of which serves to retain the member comprising the walls 25 and 26 within the housing comprising the walls 14 and 15.

Removably positioned on the non-circular bolt 29 is a block 32 to which is secured the inner end of a helical spring 33, the outer end thereof being detachably connected to a pin 34 that is seated in wall 25. This spring 33 is normally under tension and holds the housing comprising the walls 25 and 26 in position, as illustrated by dotted lines in Figure 3.

Formed in the annular wall 26 is a slot 35 which forms a port that is adapted to register with port 17 and formed in said wall 26 is a second slot 36 which provides a port that is adapted to register with port 18. Pivottally connected to the outer end of arm 27 is a rod 37 and pivottally connected to the other end of this rod is one end of a crank arm 38 that is preferably mounted on a part 39 of the spark control mechanism associated with the engine, or, if desired, this crank arm may be connected with a part of the gas control mechanism.

The operation of my improved air inlet and mixing device is as follows:

- When part 39 of the spark or gas control mechanism is actuated, crank arm 38 will be swung laterally a short distance, thereby correspondingly swinging arm 27 through push rod 37 and thus the housing comprising the walls 25 and 26 will be rotated within the fixed housing and the ends of the slots 35 and 36 will be brought into register with the ports 17 and 18 respectively.

On the suction stroke of the engine, air will be drawn through tubular member 23 and will pass through ports 17 and 35 and from thence through ports 36 and 18 and discharge into the intake manifold directly in the path of travel of the combustible vapor drawn therethrough and this air will, by suction, be drawn through the aper-

tures 22 of the mixing plate and at the same time, a portion of the combustible vapor will be drawn through said apertures, thereby effecting a very thorough mixture of the air with the combustible vapor, and such mixture will pass into the combustion chambers of the engine.

As the spark control mechanism is operated to advance the spark to normal running position, the ports 35 and 36 are brought into full register with the ports 17 and 19 as shown in Figure 3, and thus a considerable volume of air is permitted to enter the intake manifold to mix with the vapor passing therethrough, and thereby materially increasing the efficiency of the engine.

Should any of the connections between lever 27 and member 39 become broken, the power stored in spring 33 will act to rotate the inner housing so that the ports 35 and 36 are out of register with the ports 17 and 18, thereby cutting off the passage of air through the device. By extending the tubular connection 23 so that its inlet end is immediately adjacent to the exhaust manifold, the air drawn into said member 23 will be preheated to a certain degree and in such condition said air will readily mix with the explosive vapor in the intake manifold.

The spring carrying block 32 is removably mounted on the non-circular block 29 so that it can be readily removed and reversed in position and which arrangement is essential in order that the device may be used on different forms of intake manifolds.

An air inlet and mixing device of my improved construction can be easily and cheaply manufactured, can be applied to practically all forms of intake manifolds and said device possesses superior advantages in point of simplicity, durability and general efficiency.

It will be readily understood that minor changes in the size, form and construction of the various parts of my improved air inlet and mixing device can be made and substituted for those herein shown and described without departing from the spirit of my invention, the scope of which is set forth in the appended claims.

I claim:

1. In an air inlet and mixing device for internal combustion engines, a cylindrical housing adapted to be secured to the intake manifold of the engine, a perforated mixing plate carried by said housing and projecting into and across the passageway through the intake manifold, a second cylindrical housing mounted for rotary movement within the fixed housing, there being ports formed in the cylindrical walls of said housings, which ports are adapted to register when the rotatable housing is shifted to

- a certain position, and operating connections for said rotatably mounted housing.
2. An air inlet and mixing device for internal combustion engines comprising a housing formed in two parts, each of which is formed with an annular flange, the flange of one part being operatively arranged within the flange of the other part, one of said parts being movable with respect to the other, 10 means for holding the parts of the housing in assembled relation, a spring associated with the movable part of the housing and tending to rotate the same in one direction, the flanges of the parts of the housing being 15 provided with ports which are adapted to register when the movable part of the housing is shifted to a certain position, and a perforated mixing plate carried by the relatively stationary portion of the housing and 20 extending into and across the passageway through the intake manifold with which the device is associated.
3. An air inlet and mixing device for internal combustion engines comprising a housing formed in two cylindrical parts, one of which is movable with respect to the other, means for holding the parts of the housing in assembled relation, a spring associated with the movable part of the housing and tending to rotate the same in one direction, the peripheral walls of said parts of the housing being provided with ports which are adapted to register when the movable parts 30 of said housing is shifted to a certain position, a perforated mixing plate carried by the relatively stationary portion of the housing, and extending into and across the passageway through the intake manifold with which the device is associated, and an arm projecting from the movable part of the housing, which arm is adapted to receive operating connections.
4. An air inlet and mixing device for internal combustion engines comprising a housing formed in two parts, one of which is movable with respect to the other, means for holding the parts of the housing in assembled relation, a spring associated with the movable part of the housing and tending 40 to rotate the same in one direction, the parts 45 of the housing being provided with ports which are adapted to register when the movable housing is shifted to a certain position, a perforated mixing plate carried by the relatively stationary portion of the housing and extending into and across the passageway through the intake manifold with which the device is associated, and an air inlet tube projecting from one of the ports in the relatively stationary housing. 55
5. In an air inlet and mixing device for internal combustion engines, a relatively stationary housing having a circular wall provided with inlet and outlet ports, a perforated mixing member projecting from said housing around the outlet port which perforated mixing member is adapted to project into and across the passageway in the intake manifold of the engine with which the device is associated, a movable housing having a circular wall engaging the circular wall of said stationary housing and provided with ports which are adapted to register with the inlet and outlet ports in the wall of said stationary housing, and means 60 for shifting the position of said movable housing. 65
6. In an air inlet and mixing device for internal combustion engines, a relatively stationary housing provided in one of its walls with inlet and outlet ports, a perforated mixing member projecting from said housing around the outlet port which perforated mixing member is adapted to project into and across the passageway in the intake 70 manifold of the engine with which the device is associated, a movable housing associated with said stationary housing and provided with ports which are adapted to register with the inlet and outlet ports in said stationary housing, a spring arranged within 75 said movable housing and associated therewith for tending to rotate the same in one direction, and means associated with said movable housing for moving it against the 80 resistance offered by said spring. 85

In testimony whereof I hereunto affix my signature this 21st day of October, 1919.

FRANK C. TABLER.
